UNITED STATES PATENT OFFICE.

ALBERT DOBSON, OF ST. LAMBERT, QUEBEC, CANADA.

PASSENGER-CAR EQUIPMENT.

Application filed January 15, 1923. Serial No. 612,796.

The invention consists essentially of the novel features pointed out broadly and specifically in the claims for novelty following a description containing an explanation in detail of an acceptable form of the invention.

The objects of the invention are to afford a convenience to passengers in railway trains, so that it will be quite unnecessary to lock 10 lavatory compartments while the train is standing or travelling within the limits of cities and subways and other places where it is desirable to keep the road bed free from waste matter; to insure reliable operation of 15 the parts notwithstanding climatic conditions; to avoid disagreeable odors returning to the car compartment, and generally to provide in the construction of railways a simple, durable and effective container for 20 the purposes aforesaid readily operable by the porter and easily maintained in a sweet condition.

In the drawings,

Figure 1 is a vertical sectional view of the 25 bowl showing the slide valve and connections.

Figure 2 is a plan view of the top broken to disclose a plan of the steam connections.

Figure 3 is sectional detail showing a fragmentary view of the bowl and the wash 30 guard at the overflow opening.

Figure 4 is a cross sectional view of the steam radiator and casing.

Figure 5 is a fragmentary view of the slide 35 casing showing a wedge.

Figure 6 is a detail showing the fourway valve connection to the flushing pipe.

Figure 7 is a detail showing a plan view of the rack in the operating gear.

Figure 8 is a detail showing a cross sectional view of the rack, including the gear and guide rollers.

Figure 9 is a detail of the slide valve, flushing lever and operating handle.

Figure 10 is an end elevation of the operating handle and lever showing the press button cam.

Figure 11 is a perspective detail of the slide valve from below.

Figure 12 is a perspective detail of the slide valve from above.

Figure 13 is a perspective view of the sliding valve.

Figure 14 is a cross sectional side view of the sliding valve.

Figure 15 is a cross sectional front view of the sliding valve.

Like numerals of reference indicate corresponding parts in the various figures.

Referring to the drawings, the bowl or 60 hopper 1 converges to the exit opening 2 at the bottom end and is formed with the upper flange 3, having the flat feet 4 on the under side adapted to be machined to agree in fitting with the thickness of the upper flooring, 65 said hopper 1 also having the intermediate flange 5 on which the locking ring 6 is mounted, said locking ring having the flange 7 internally threaded.

The bowl 1 is made with the overflow passage 8 at one side which is protected at the entrance by the shelf or wash guard 9. The wash guard or shelf 9 opens in the upturned flange 10, this opening 11 forming an outlet through which the water flows, when it rises 75 above the shelf, otherwise the latter acts as a guard against the wash or slopping of the water within the bowl due to the movement of the car.

The cover 12 is fastened on to the bowl 1 80 by the screws 13 through the margin 14 into the feet 4 and has the opening 15 into which the bowl of the car closet fits. The strainer lug 16 from the cover 12 projects downwardly in front of the slot 11 to avoid the 85 clogging up of the overflow passage and the consequent freezing of the overflow water.

The vent pipe 17 is in vertical alignment with the overflow pipe 19 consequently there is an uninterrupted passage from the under 90 side of the car 18 through the interior and the roof, the deodorizer 20 being supported by the bracket 21 intermediately of the height of said vent pipe.

The flushing channel 26 is in the form of 95 a groove 22, in the boss 23 from the under side of the cover 12 and therearound, covered in by the grooved ring 24 secured through the flange 25 to said boss, said ring being spaced from said boss to form the outlet 100 27 directed on all sides to the wall of the bowl. The inlet 28 to the channel 26 is made through the cover and is connected by a pipe 29 to a valve 30.

The fourway valve 30 is screwed to the 105 floor through the base 31 and is in the form of a cross and is of conventional type having the four ports 32, 34, 35 and 36 and the central chamber 33. The valve stem boss 37 is on the side opposite the threaded plug open- 110

ing 38 in the other side. The valve seat 39 surrounds the port 40 at the entrance to the passage 41 connected to the flushing pipe 29.

5 The valve 42 closes the port 40 and is secured to the stem 43 slidably mounted in the screw plug 44 screwed into boss 37 which is pierced and threaded accordingly for stem and plug. The guide plug 45 is screwed into the plug opening 38 and has the stem hole 46 for the inner end of the stem 43 and forms a stop for the spring 47 encircling the stem thus keeping the valve 42 to its seat 39 except during the flushing operations.

15 The press button 48 forms the head of the stem 43 and is rounded off on the outer surface 49 to facilitate the operation thereof.

The port 34 of the valve 30 is joined through the coupling 50 to the pipe 29 and 20 the port 32 is shown as connected to the pipe 51 from the tank beneath the flooring and illustrated by parallel lines as being in Figure 1 behind the vertical shaft 56. In Figure 6 one port is shown 25 as closed by the screw plug 52 and another by the screw cap 53, thus showing the possible variations in the ports according to conditions of installation.

The floor plate 55 is secured to the floor 30 at a suitable distance from the four way valve 30 and forms a bearing for the vertical operating shaft 56, on which is fixedly mounted the crank lever 57 having the operating handle 58 at one end of its lever 35 arm 59 and the balance weight 60 at the other end beyond the point.

The central lug 61 projects from the handle end of the arm 59 and to this the dog 62 is pivotally secured through the lugs 63 and 64.

40 The dog 62 is formed with a curved cam face 65 adapted to engage the press button 48 so that when the crank lever is operated in one direction the stem 43 is pushed inwardly and opens the valve 42 for flushing purposes. The stops 66 and 67 are provided for limiting the strokes of the operating handle 58. The return stroke does not affect the position of the valve stem 43 as the dog 62 is formed with a tapered end and long 45 bevelled surface 68, which enables it to ride over the press button 48 on account of its pivotal mounting, therefore the flushing of the bowl only occurs during the opening stroke, when the outlet from the bowl is 50 wide open as explained more fully herein- 55 after.

The shaft 56 is journalled at its lower end in the bracket hanger 69 secured to the under side of the car body and the rack 70 is 60 also slidably supported from said bracket.

The rack 70 is formed as an internal gear having the teeth 71 along one side of the longitudinal pinion passage 72 which is parallel to the roller guide slot 73, the latter being open on the inside to the pinion

passage 72, so that the guide roller 74 journalled on the spindle 75 secured in the bracket 69 may engage the guide discs 76 and 77 mounted on the shaft 56 and flanking the pinion 78, which coacts with the teeth 70 71 in reciprocating the rack 70.

The roller 74 is spool shaped, that is to say recessed centrally at 79 leaving the friction disc surfaces 80 and 81 at the ends to engage the discs 76 and 77 and so maintain a good 75 operative coaction between the pinion and rack teeth and at the same time eliminate any rattling.

The shaft 82 is secured in the socket 83 forming the projecting end of the rack 79 80 and is held by the cotter pin 84, though any suitable form of coupling may be used.

The shaft 82 at its other end is secured to the slide valve 85 between the lugs 86 and 87 by the cotter pin 88.

85 The slide valve 85 is hollow forming the hot air chamber 89 open at the shaft end and closed at the other end and having through the sides the circulation vents 90. The bottom of the slide is made with the 90 longitudinally bevelled runners 91 forming wedge surfaces in closing operations. The top of the slide is slightly raised above the edge portions and slopes to an inclined drain 95 93 discharging over the end towards each 95 side of the top, thereby keeping the valve surface free of liquid accumulations.

The slide valve 85 is mounted on the ledges 94 and 95 at the sides of the valve chamber 96, said ledges forming slide ways 100 for the valves, these ledges being depressed at 97 to form pockets for the wedge blocks 98 seated on the wedge bases 99, both wedge blocks and bases being held in place by the lugs 100 forming continuations of the chamber walls, said wedge bases 99 being adjusted by the set screws 117. The runners 91 slide on the ledges 94 and 95 and therefore engage the wedge blocks 98 slightly above the ledge surfaces at one end, therefore the slide 110 valve 85 is wedged tightly to its seat 101 formed by the copper packing ring 102 encircling the lower end of the bowl 1 in the recess 103.

115 The steam radiator 104 is preferably integral with the casing of the valve chamber 96 and extends above the top wall, and it may here be mentioned that in the outer wall of the chamber 96 the cap 105 is secured by the bolt 106, and it is through this 120 cap 105 that the shaft 82 extends to the slide.

The steam radiator 104 is formed of a casting superposed on the valve chamber 96 and divided by the longitudinal partition 107 125 meeting the circular partition 108 surrounding the bottom of the bowl, thereby forming an inlet passage 109 connected by the pipe 110 to the train line steam pipe and forming an outlet passage 111 connected to the 130

exhaust pipe 112 and to a vapor regulator 113, the said inlet passage communicating with the said outlet passage through the circular passage 114 encircling the bowl, 5 said circular passage 114 having its walls slightly elevated to form the threaded projecting portion 115 of the casing adapted to be screwed into the locking ring 6 supported by the flange 5 around the bowl 1.

10 The wool fibre insulation 116 is securely packed around the bowl 1 over the steam radiator 104 to maintain the parts in a comfortable condition.

15 In the operation of this device the waste matter from the bowl in the car compartment is let into the under car waste bowl with the accompanying flushing water and remains therein while the train is at a station or within the limits of a city or other 20 prohibitive place, and during that period the noxious odors float upwardly through the vent pipe where they become disinfected and harmless through treatment with the deodorizer in said pipe.

25 During the travel of the train in country parts away from inhabited localities, the crank lever is operated by means of its handle and this draws the rack along, and through the shaft connection removes the 30 slide valve from the outlet opening at the bottom of the bowl and coincidentally the dog at the end of the lever engages and presses the button of the water valve stem, which opens the water supply, and as this is under 35 pressure the water flows through the four way valve body into the pipe connecting said body with the flushing channel. The said flushing channel surrounds the upper end of the bowl where the flushing water is 40 expelled through the outlet on to the inside surface of the bowl. The crank lever is then turned to perform its return stroke, and the dog rides over the press button and the slide valve returns to its closed position 45 being wedged tightly to its seat by the contact of the runners and wedge blocks. The slide valve is kept constantly warm by the steam radiator, which provides hot air within it as well as around all parts exposed 50 within the valve chamber. The bowl is kept warm at the outlet, so it is quite impossible for ice to collect and choke up the outlet and surroundings and prevent the operation and the functioning of the slide valve.

55 What I claim is:—

1. In passenger car closet equipment, a bowl under the car having an outlet at the bottom end and an overflow exit adjacent to the upper end, and an overflow passage 60 therefrom, a cover for said bowl having a pipe connection above said exit and passage and forming an upward continuation of the latter, a vent pipe attached to said pipe connection and extending through the car roof.

2. In passenger car closet equipment, a bowl under the car having an outlet at the bottom end, a valve closing said outlet, a cover for said bowl having an opening for an upper bowl and a water inlet connection 70 and feed pipe therefrom, a valve body having optional inlets and a central valve chamber and a valve having a stem therefrom and a press button on the end thereof, and means for operating said stem. 75

3. In passenger car closet equipment, a bowl under the car having an outlet at the lower end, a slide valve closing said outlet, a slideway for said valve, supporting members under the car, a crank lever and shaft, 80 a pinion mounted at the lower end of said shaft, guide discs flanking said pinion, a rack having a longitudinal pinion passage and coacting teeth on one side thereof and a roller journalled on a pin projecting through said slot and secured in said bracket, an operating handle for turning said shaft and pinion and coincidentally opening the valve controlling the water feed to the flushing channel of the bowl, and a connecting rod 85 from said rack to said valve.

4. In passenger car closet equipment, an under car waste bowl having an outlet at the lower end, a valve casing secured to said bowl and having ledges at the sides forming slideways and having wedge pockets intermediate of their length, wedge blocks rocking in said pockets and a slide valve having longitudinally bevelled runners operating on said slideways and wedge blocks 95 100 and closing the bowl outlet.

5. In passenger car closet equipment, an under car waste bowl having an outlet at the lower end thereof, a valve casing secured to said bowl and having ledges at the 105 sides forming slideways and wedge pockets in said slideways, wedge arms having rocker under surfaces, base blocks formed to receive the rockers and contained in said pockets, and a slide valve having a wedging surface in the underside sliding on said slideways and wedge blocks and closing the outlet. 110

6. In passenger car closet equipment, an under car waste bowl having an outlet at 115 the lower end, a valve casing at the lower end of said bowl formed with slideways along the sides and pockets therein, wedge blocks having rocker under surfaces, base blocks formed to receive said rockers, adjusting screws for settling said bases, and slide valve having runners co-operating with said blocks in wedging the valve tightly to its seat at the lower end of said bowl. 120

7. In passenger car closet equipment, an under car waste bowl having an outlet at the lower end and valve seat therearound and outstanding flange above said outlet, a freely rotatable locking ring supported on 125 130

4
said flanges and having an internally threaded flange therefrom engaging the valve mechanism, a radiator casing having an upwardly projecting externally threaded portion encircling said bowl and screwed into said ring flange and passages to and from said circular portion having inlet and outlet respectively, a valve casing rigid with said radiator casing and having walls heated thereby and having valve slideways, and a slide valve suitably operated on said slideways and closing the outlet of said bowl.

8. In passenger car closet equipment, an under car waste bowl having an outlet at the lower end and a valve seat, a casing secured by a retaining ring to the lower end of the bowl and including a valve chamber and slideway, a steam passage having inlet and outlet and extending around the bowl above said valve chamber and heating the latter by dry hot air, and a slide valve operating in said valve chamber and closing the lower end of said bowl.

9. In passenger car closet equipment, an under car waste bowl having an outlet at the lower end, a valve casing secured to said bowl, a valve sliding in said casing and adapted to close the outlet, a cover for said bowl having a channelled rib therearound and a water inlet through said rib, and a flanged channelled ring rigidly secured to the under side of said cover and forming with said rib a water channel having a continuous outlet facing the wall of the bowl.

35 10. In passenger car closet equipment, an under car waste bowl having an outlet at the lower end, a valve casing secured around and about said outlet, a valve slidably supported in said casing and closing said outlet, a cover having a hopper opening thereinto, said bowl having an overflow exit, a channelled flushing passage on the underside, a water inlet into the latter and a vent opening over said overflow exit, a water supply pipe to said water inlet and valve

control and a vent pipe from said vent opening leading through the car roof.

11. In passenger car closet equipment, an under car waste bowl having an outlet at the lower end, an overflow exit and passage, and a wash guard in the form of a shelf immediately beneath said overflow exit and formed with an upright wall from its front and side edges and an opening in one of said walls, a cover having a flushing channel on the underside, a hopper opening therethrough, a water inlet and a lug fitting into said shelf wall opening and forming a strainer bar and means for securing said cover to said bowl.

12. In passenger car closet equipment an under car waste bowl having an outlet at the lower end, a slide valve closing said outlet having upper, lower and end walls and open at the front side and on the top a surface sloping to a surrounding drain channel, a shaft secured to the longer bottom of said slide valve, a valve casing secured to said bowl and having slideways for said valve and means for operating said shaft.

13. In passenger car closet equipment, an under car waste bowl having an outlet at the lower end thereof, a slide valve closing said outlet, a valve gear for operating said valve, a pipe leading to a flushing channel in said bowl, a valve body connecting to the water supply and said flush pipe and having its other ways plugged and a valve seat and a spring-held valve in the centre thereof and a stem from said valve terminating in its outer end in a press button, a balanced crank lever suitably mounted and a dog pivotally secured at an end of said lever and having a cam face engaging and pressing said button on one stroke and a bevelled tapering end adapted to ride over said button on the return stroke.

Signed at Montreal, Canada, this 11th day of January, 1923.

ALBERT DOBSON.
